Attorney.

UNITED STATES PATENT OFFICE

GORDON DON HARRIS, OF SOUND BEACH, CONNECTICUT, ASSIGNOR TO THE INDUSTRIAL DRYER CORPORATION, OF STAMFORD, CONNECTICUT, A CORPORATION OF CONNECTICUT

CASING TOBACCO

Application filed November 28, 1928. Serial No. 322,433.

This invention pertains to casing tobacco without injury thereto.

It has long been recognized that the quality of tobacco, such as tobacco used for cigar wrappers, would be greatly improved if the prevailing mode of surface wetting, such as by dipping or spraying, or both, and subsequently, shaking could be eliminated.

My process is a method of casing tobacco without dipping, spraying, or surface wetting, and it overcomes the effects resulting from modes of treatment above described.

The major object of this invention is to humidify or case tobacco to such a degree that it is in the best possible condition for working without lessening the quality of the product in any manner whatsoever, by charging the conditioning gas to substantial saturation with water vapor.

20 My invention in one phase comprises, first, cooling the tobacco by exposing it to air which may be either dry air or humidified air, and, second, exposing the tobacco to the action of humidified air the temperature of 25 which is increased.

Under the conditions recited, the tobacco assimilates moisture from air which is charged with moisture to substantially the point of saturation, although the temperature of the humidified air is maintained at a point at which the heat present in the air has no injurious effect on the tobacco.

It is known that tobacco is required to be permeated with moisture to place the tobacco in workable condition, and my process makes it possible to condition the tobacco without detriment thereto.

One form of apparatus suitable for the practice of my process is shown in the accompanying drawing, wherein the figure illustrates diagrammatically a longitudinal sectional view through the said apparatus.

A designates a products chamber within which leaf tobacco is supported in a desirable way, as by means of rods or bars B. The floor *a* of the chamber is perforated at *a'*, and below this floor is a duct C. Above the products chamber is a water tank D, through which passes a series of vertical tubes *d* opening into the products chamber.

At the ends of the products chamber are vertical flues E, F, connecting at their lower ends with duct C and at their upper ends with a horizontal duct or chamber G, the latter being above the tank D and said chamber functioning as a humidifying chamber or duct. A closed path for the circulation of air is afforded by products chamber A, humidifying chamber G, and flues or ducts C, E, F, so that air will flow into and out of the products chamber by way of perforations *a'* and tubes *d*.

Air is circulated by one or more fans H positioned in flues E, F, or in humidifying chamber G.

I are air coolers shown positioned within the vertical flues E, F, said air coolers being shown as coils having valved pipes *i*, *i'*, for controlling the flow of a cooling agent into and out of the coils, said cooling agent being of any kind or nature, such as cold water. For the discharge of the water of condensation, trays *j* are below the coils, and from said trays extend pipes *j'* for carrying the water away from the circulatory path.

The air circulated by the fans I flows through chamber G and above the water tank, D, and at such period of flow, the air is charged with water vapor to substantial moisture saturation. The water vapor is generated by heat supplied to the water tank D, and as one means for the heat supply required for the vaporization of water, there is shown an electrical heater J the members or units of which are submerged in the water of tank D and to which members or units an electrical current is supplied from a suitable source.

The flow current is controllable and regulatable by electrical means, such as a switch and appropriate mechanism, whereby the current may be cut off and admitted as required or desirable.

Water vapor is generated by heat to the exclusion of air, and such vapor emanates from the water and is diffused into the air flowing in chamber or duct C, with the result that a true humidity is imparted to the air, the latter functioning as a carrier for humidity. Thus the moisture generated in one

chamber is conveyed by the air flow to the products chamber, the tobacco in which assimilates moisture from the air flowing through said products chamber.

In the service of the machine, tobacco in leaf form is placed within the products chamber, and the fan is set in motion for circulating air through said products chamber and the humidifier, and into contact with the coolers. The humidifier generates water vapor which is picked up by the air so as to charge the air with moisture to substantial saturation. Air flowing into contact with coils J is cooled to a desired temperature and such cooled air flows into the products chamber for cooling the tobacco and decreasing its temperature.

One desirable mode of procedure for casing tobacco is to shut off the vapor generator, and to circulate air into contact with the coolers acting to cool the air to a desired temperature, and such cooled air flows through the products chamber for cooling the tobacco therein, reducing the temperature of the product. The tobacco having been cooled, the vapor generator is brought into service by setting up the flow of current through the submerged heater, for generating water vapor, the same being diffused into the flowing air with the result that the air is humidified to substantial saturation.

The humidified air is circulated through the products chamber and thus the tobacco leaf, in a cool condition, is exposed to the action of the humidified air, with the result that the tobacco assimilates moisture from the flowing air. The cool tobacco is at a temperature less than the temperature of humidified air, and the moisture present in the air is assimilated by condensation in the tobacco, the moisture being diffused into all parts of the leaf. The operations are conducted efficiently without alteration in the physical characteristics of the leaf, and the treatment is carried out with expedition and economy.

Cooling of tobacco prior to the humidification has the effect of equalizing the temperature of all the leaves and permits more uniform casing of all the leaves in the hand when subsequently treated with humidified gas.

In the exposure of the leaf to air at the first stage of the treatment, the air may be dry or humidified air, the temperature being such as to cool the tobacco. If desired, the air circulated at the first stage may be humidified by service of the vapor generator, but at this first stage the coolers are effective in cooling the air by reduction in temperature. At the second stage of the treatment, the humidifier is in service for the generation of water vapor diffused into the flowing air, and said humidifier is controllable for raising the temperature of the operating air, concurrently with the diffusion of moisture,

the coolers being either out of service or in service, as required, at said second stage.

While the present invention has been described employing air as the treating fluid, I wish it to be clearly understood that any other gas suitable for the purpose may be employed with equally desirable results, consequently, wherever the term "air" is employed, this term is intended to include other gases having properties suitable for treating the tobacco.

Having thus fully described the invention, what I claim as new and desire to secure by Letters Patent is:

1. A process of casing tobacco comprising circulating a gas in a closed circuit through a zone containing the tobacco and over the surface of a body of liquid, cooling the gas as it flows from the chamber containing the material to be treated to the body of water, and subsequently heating the body of water to generate water vapor, diffusing the water vapor into the gas to effect substantially complete saturation of the gas with vapors and to heat the gas, and circulating the gas without cooling, in contact with the tobacco.

2. A process for conditioning tobacco comprising supplying moisture to a conditioning gas by passing the gas over a body of water, conveying the gas into a zone containing the tobacco, and recycling the gas over the surface of the body of water, cooling the gas in one stage of treatment as it passes from the zone containing the tobacco to the body of water and in a subsequent stage heating the gas by heating the body of water to effect the generation of vapors to supply heat to the gas and to substantially completely saturate the gas with moisture, and circulating the gas cyclically over the heated body of water and through the zone containing the tobacco without cooling.

3. A process for casing tobacco comprising circulating a gas in a closed circuit, including a conditioning zone and a zone containing the tobacco to be treated, maintaining a body of water in the conditioning zone over the surface of which the gas passes in circulating through the closed circuit, cooling the tobacco in the zone containing the same by cooling the gas while passing from one zone to the other, and subsequently supplying heat to the body of water in the conditioning zone to raise the temperature of the gas passed thereover and to substantially completely saturate the gas with moisture, and passing the heated substantially completely saturated gas in contact with the tobacco to case the same.

4. A process for casing tobacco comprising circulating a gas in a closed circuit including a conditioning zone and a zone containing tobacco which has been precooled, passing the gas over the surface of a body of liquid, heating the liquid to vaporize the

same, and controlling the rate at which heat units are supplied to the liquid body to effect substantially complete saturation of the gas with vapor and to maintain the temperature of the gas above the temperature of the precooled tobacco, and passing the gas while substantially completely saturated with vapor in contact with the precooled tobacco, the saturation of the gas and the heating of the gas being effected exclusively by the heat supplied to the body of liquid.

5. In the art of humidifying materials, the process which consists in generating water vapor by the action of heat in the presence of water, cooling air, substantially completely saturating the air with the water vapor, the heat in which conditions the air in the presence of the water vapor for the absorption of such vapor whereby the air is substantially completely saturated, exposing the material to the treated air to cool the material, and subsequently exposing the material to substantially completely moisture saturated air at a higher temperature to effect the assimilation of moisture in the material.

6. In the art of casing tobacco, the process which consists in exposing tobacco to cooled air to reduce the temperature of the tobacco, subsequently setting up a flow of air at a higher temperature, vaporizing water by the action of heat in the presence of water to the exclusion of air, thereby generating water vapor, charging the flowing air with water vapor to a substantially complete saturation, and exposing the cooled tobacco in leaf form to the access of the substantially complete moisture saturated air.

7. In the art of casing tobacco, the process which consists in setting up a flow of cooled air, vaporizing water by the action of heat in the presence of water to the exclusion of air, thereby generating water vapor, charging the flowing air with water vapor to a substantially complete saturation, and exposing tobacco in leaf form to the access of the substantially complete moisture saturated air, and subsequently exposing the cooled tobacco to air at a higher temperature and which is substantially completely saturated with moisture.

In testimony whereof I have hereto signed
my name this 26th day of November, 1928.

GORDON DON HARRIS.
